and the *Leucostoma* genus. The *Leucostoma* genus is a small genus of fungi with only four species. The genus is characterized by the presence of a white, waxy, or leathery cap, and a white, powdery or granular spore mass. The species are: *L. ciliatum*, *L. ciliatum*, *L. ciliatum*, and *L. ciliatum*.

WORK HOLDING ATTACHMENT FOR DRILL PRESSES

John T. Betts, Los Angeles, Calif.

Application August 23, 1943, Serial No. 499,684

1 Claim. (Cl. 77—63)

1

The present invention relates to improvements in work holding attachments for drill presses and has for an object thereof the provision of such a device which will effectively hold work in position for drilling.

Another object of the invention is the provision of a work holding device which can be detachably mounted on a conventional drill press.

A further object of the invention is the provision of a drill press work holder having means for engaging work pieces having angular as well as curved contours.

Still another object of the invention is the provision of an attachment of the aforesaid character which is relatively simple and durable in construction and efficient in use.

Other objects and advantages of the invention will become apparent as the description progresses.

In the accompanying drawing forming a part of this specification and in which like numerals are employed to designate corresponding parts throughout:

Figure 1 is a side elevational view of the device in operative position on a drill press.

Figure 2 is a top plan view of the assembled device.

Figure 3 is a detail sectional view taken on the vertical plane indicated by the line 3—3 of Figure

Figure 4 is a perspective view illustrating a

Referring to the drawing, wherein for the purpose of illustration is shown a preferred example of the invention, 5 generally designates the body of the device which essentially embodies an elongated rectangular plate. At its outer end the plate 5 has one corner recessed to form a right angular work engaging notch 6 preferably having its greatest dimension longitudinally of the plate as shown at Figure 2. This outer end portion of the plate is also shaped to provide a re-entrant recess 7 medially of the longitudinal edge of the notch 6 to form an inwardly tapering V-shaped work engaging notch.

The opposite end of the plate is shaped to provide medially of its side edges, an arcuate concavity 8 designed to conform to the circumferential contour of a drill press column indicated at C of Figure 1. At each side of the concavity 8, the inner end edge of the plate is provided with a pair of end faces 9 disposed obliquely in a direction transverse of the plate, for a purpose which will be later described.

To the inner end of the plate 5 are removably

2

connected a pair of complementary clamp sections 10 each of which embodies an arcuate portion 11 having radially extending lugs 12 and 13 at the respective ends thereof. The lugs 12 of the complementary sections 10 are adapted, in assembly, to assume contiguous parallel positions and one may be formed with a smooth through bore 14 while the other is provided with an internally threaded bore 15 to receive the threaded shank of a connecting cap screw 16. The lugs 13 at the opposite ends of these sections are designed for assembly with the oblique transverse faces 9 of the plate and, with this in mind, each of these lugs has its outer edge 17 disposed at an acute angle with the outer face of the lug to assume alignment with the longitudinal edges of the plate when associated therewith. Furthermore each of the lugs 13 has a smooth through bore 18 adapted to assume alignment with an internally threaded bore 19 in the plate so as to receive the threaded shank of a cap screw 20. As will be noted from Figure 2, the sections 10 are formed to assume circular assembly relation with the plate to embrace the drill press column C, the said clamp sections and the plate preferably having complementary boss sections 10^a projecting below the bottom face level of the body in circular arrangement to rest upon the table of the drill press.

30 By suitable turning of the screw 16 the column clamping end of the device may be loosened to be swung in a circle about the column C as a center to center the work beneath the drill bit D and to permit angular adjustment of the body to a non-working inoperative position or to the required operative position for holding work pieces for drilling at which time the clamp is tightened to hold the body against accidental movement. If the work piece has an angular contour as indicated at W it is arranged to fit within the right angular recess or notch 6 and is firmly held in proper position for drilling by the drill bit indicated D. If, on the other hand the work piece has a circular contour as indicated at Y it is fitted in the V-shaped notch 7. By loosening the set screw 16, and by placing a sample of the work on the table of the press and in contact with the walls for the recess 7, the plate 5 may be swung to center the sample with the drill bit D. The screw 16 is then tightened to secure the plate in this position, so that all subsequent samples of the same work will be automatically centered on being placed on the table in contact with the side walls of the recess 7, as suggested in Figure 2. This is also true of the notch 6. If desired the

work may be secured in a clamp or jig 21, and the jig inserted in the angular notch of the work holder, as suggested in Figure 4. In this figure the plate of the work holder is designated 5^a, and the angular notch of the work holder 6^a. The plate 5^a may also be provided with angular notches 6^b for the reception of cylindrical work pieces or the corner of a clamp or jig.

The clamp end of the work holder may be babbitted. The babbitt 22 may be poured between the wall of the clamp end of the work holder and the column or it may be secured to the several parts of the clamp end of the work holder as shown in the drawing.

It is to be understood that the forms of my invention herewith shown and described are to be taken as preferred examples of the same and that various changes relative to the material, size, shape and arrangement of parts may be resorted to without departing from the spirit of the invention or the scope of the subjoined claim.

Having thus described my invention, I claim:

In a work holder of the character described, an elongated rectangular shaped plate, the outer end portion of the plate having an angular recess in

one corner thereof and a V-shaped recess extending inwardly from a wall of said first recess, and adjustable clamp means at the opposite end of the plate for attaching the same to the column of a drill press for movement in a circle with the drill press column as a center.

JOHN T. BETTS.
